MOLD FOR FROZEN CONFECTION

Earl S. Tupper, Smithfield, R.I., assignor to Tupper Corporation, North Smithfield, R.I., a corporation of Delaware

Filed Oct. 25, 1956, Ser. No. 43,523

Term of patent 14 years

(Cl. D44—1)

Figure 1 is a view in perspective of a mold for frozen confection embodying my new design;

Figure 2 is an exploded view in perspective thereof;

Figure 3 is a top plan view thereof;

Figure 4 is a front view in elevation thereof; and

Figure 5 is a side view in elevation thereof.

I claim:

The ornamental design for a mold for frozen confection, substantially as shown.
